HANDLE FOR MULTICELLULAR FOLDING BOXES

Marshall I. Williamson, New Haven, Conn., assignor to Federal Paper Board Company, Inc., Bogota, N.J., a corporation of New York

Filed July 19, 1957, Ser. No. 672,991

9 Claims. (Cl. 229—52)

This invention relates to improvements in the construction of handles for compartmented or multicellular folding boxes.

Multicellular folding boxes equipped with a carrying handle serve as carriers for bottles, jars, cans, or other merchandise.

The handles may assume a wide variety of forms which may be classified in various ways.

One classification may be made on the basis of whether the handle is integral with, or separate from the multicellular box.

Integral handles usually are in the form of a tall center partition in the multicellular folding box having a hand hold near the top. This construction has the advantage of simplicity, but the disadvantage of requiring a substantial additional amount of board, which raises the cost of the carrier. A further disadvantage of the integral handle is that it interferes with the stacking of loaded carriers into pyramids if the handle partition is tall and extends above the tops of the bottles or other merchandise. If the integral handle is short and terminates below the tops of the bottles, it is inconvenient to grasp.

Distinct from the aforementioned integral handles are the handles which are separate from the box structure, require assembly with the multicellular box, and are detachable therefrom. This invention relates to the latter class of handles which offers among other features the advantage that the size of the box blank is considerably smaller than in the case of a construction employing an integral handle.

Handles may also be classified on the basis of the material from which they are made. Various forms of handles have been proposed employing a material different from the material of the multicellular box, generally wire. Wire handles have certain advantages among which may be mentioned great strength and a comfortable shape which generally is so designed as to permit the handle to be lifted above the tops of the bottles for carrying and to be depressed below the tops of the bottles for stacking.

A disadvantage of wire handles is their cost which tends to make them uneconomical except for carriers making several round trips between the bottler or packer and the consumer.

Detachable handles may also be constructed from paperboard, generally of a heavier caliper than the box to provide the necessary strength. This invention provides a handle construction of great strength which permits use of board of the same grade and light caliper as the box.

As will become apparent from the following description, the handle is easy to assemble with a multi-cellular box structure and is so designed that it does not interfere with the loading of the carrier by conventional and established loading equipment. The handle is so designed that it may telescope with regard to the multi-cellular box structure and is provided with structural elements which cause it to engage the multicellular structure automati-

cally. This facilitates the assembly and eliminates the danger of accidental disengagement.

If a multicellular box structure is to serve as a container for a plurality of bottles or jars to be transported, the glass contact between bottles and jars in adjacent compartments or cells presents a serious problem. This problem is conventionally met by deep partitions or separators between the compartments or cells. This form of separation necessitates an enlarged blank of correspondingly higher cost.

Handles embodying the present invention serve as an effective separator preventing glass-to-glass contact between adjacent cells, particularly if the handle is depressed. By use of handles embodying the present invention the cost of larger box blanks providing glass separation may be saved by shifting the separating function to the handles.

These and other objects, features and advantages of the invention will appear more fully from the detailed description which follows accompanied by drawings showing, for the purpose of illustration, preferred embodiments of this invention. The invention also resides in certain new and original features of construction and combination of elements hereinafter set forth and claimed.

Although the characteristic features of this invention which are believed to be novel will be particularly pointed out in the claims appended hereto, the invention itself, its objects and advantages, and the manner in which it may be carried out may be better understood by referring to the following description taken in connection with the accompanying drawings forming a part of it, in which:

Figure 1 is a plan view of a blank from which a handle embodying the invention may be constructed;

Figure 2 is a plan view of the blank of Figure 1 after a folding and gluing operation;

Figure 3 is an end elevational view of the handle formed from the structure of Figure 2;

Figure 4 is a perspective view of a typical twin-row multicellular folding box in connection with which the handle of Figure 3 may be used;

Figure 5 is a perspective view of the multicellular box structure of Figure 4 combined with the handle of Figure 3;

Figure 6 is an elevational section view of the structure shown in Figure 5 filled with bottles to illustrate the bottle separating function of the handle, the section being taken on line 6—6 of Figure 5;

Figure 7 is a plan view of a flat blank of modified construction for a single-row carrier;

Figure 8 is a plan view of the handle of the blank of Figure 7 after an initial folding and gluing operation;

Figure 9 is a perspective view of a multicellular folding box structure combined with a handle constructed from the blank of Figure 7, the handle spanning a single partition; and

Figure 10 is a perspective view illustrating the same type of handle shown in Figure 9, the handle spanning two partitions and a cell.

In the following description and in the claims various details will be identified by specific names for convenience. The names, however, are intended to be generic in their application. Corresponding reference characters refer to corresponding parts in the several figures of the drawings.

The drawings accompanying, and forming part of, this specification disclose certain specific details of the invention for the purpose of explanation of broader aspects, but it is understood that the details may be modified in various respects without departure from the principles of the invention and that the invention may be applied to other structures than the ones shown.

The blank A shown in Figure 1 may be cut and scored in multiple from large sheets or rolls of paperboard or other suitable foldable sheet material on automatic cutting and creasing machines.

The handle blank A comprises a pair of handle panels 11 and 12 articulated along a central fold line 13. The upper portions 14 and 15 of the handle panels adjacent the central fold line 13 may be termed grip portions and may be provided with finger or hand apertures 16 and 17. In the illustrated form of handle these apertures are formed by cuts 18 and 19 defining tabs 20 and 21 which remain articulated to the grip portions 14 and 15 of the handle along the fold lines 22 and 23.

Flange panels 24 and 25 are articulated to the handle panel 11 along flange fold lines 26 and 27 extending substantially at right angles with respect to the central fold line 13. Similarly, flange panels 28 and 29 are articulated to the handle panel 12 along flange fold lines 30 and 31.

Blanked out slots 26', 27', 30' and 31' may be provided in line with the flange fold lines 26, 27, 30 and 31 to provide for greater clearance by elimination of the bead which is formed at the back of the board by the creasing tool.

Opposite flange panels 24 and 28, and also the flange panels 25 and 29, are articulated to each other along fold lines 32 and 33 which, in the flat blank, form extensions of the central fold line 13.

Diagonal gusset fold lines 34, 35, 36 and 37 extend from the intersections of the flange fold lines with the central fold line 13, preferably, although not necessarily, at an angle of 45 degrees.

Box engaging flaps 38 and 39 are articulated to the handle panels 11 and 12. These flaps are wider than the handle panels, width being measured between the flange fold lines which border the handle panels. The flaps 38 and 39 are articulated along flap fold lines 40 and 41 marking the ends of the handle panels 11, 12, as well as the ends of the flange panels 24, 25, 28 and 29.

The engaging flaps 38 and 39 are foldable back upon the handle panels and upon the flange panels to which they are articulated about the fold lines 40 and 41.

The flaps may include securing tabs 42 and 43 for adhesive attachment to the handle panels. These tabs are separated from the laterally adjoining portions of the flaps by cuts 44, 45, 46 and 47 resulting in a substantially wing-shaped outline of the lateral flap portions 48, 49, 50 and 51.

Auxiliary central folding creases 52 and 53 may be provided, the end portions 54 and 55 of which may include interrupted cuts to facilitate sharp creasing of the board along the auxiliary central creases. Angular cuts or cut scores 56 may be provided to extend from the ends of the flange fold lines. These cuts 56 promote creasing of the flaps 38, 39 in an angular direction with respect to the direction of the flange fold lines 26, 27, 30 and 31.

The blank A may be converted into handle form as follows:

The blank is first folded along the flap fold lines 40 and 41 to bend the flaps 38 and 39 into a position overlying the handle panels and their adjacent flange panels. In order to maintain the flaps 38 and 39 in folded-back position, the securing areas 42 and 43 may be fastened to the handle panels 11 and 12 by adhesive applied to the portions a, or by other means, such as staples.

At this phase of operation the tabs 20 and 21 formed by the aperture cuts 18 and 19 may also be folded back upon the upper or grip portions 14 and 15 of the handle panels, an adhesive bond between the tabs and the handle panel being optional. The resulting partially folded and pre-glued flat blank A' is shown in Figure 2. It may be shipped and stored in flat condition and may be converted into handle shape by a few further folding operations as follows:

The handle panels 11 and 12 are folded into substantially U-shape about the central fold line 13. Thereafter,

the flange panels 24, 25, 28 and 29 are folded with respect to the handle panels 11 and 12 to assume an angular position with respect to the handle panels, the direction of folding being such that the handle panels 11 and 12 are spaced less than the flange panels 24, 28 and 25, 29, which flare away from each other. Thus folded, the fold lines 40 and 41 are bent at the points at which the flange fold lines 26, 27, 30 and 31 meet them to represent substantially a biconcave figure in plan view. The folded shape is shown in Figure 5.

The flexing of the board along the flange fold line causes the folded-back wing portions 48, 49, 50 and 51 to be drawn tightly against the handle panels and their bordering flange panels, particularly along the areas in line with the flange fold lines. In this condition the engaging flaps 38 and 39 cannot be folded down and are capable of supporting a substantial load securely. Figure 3 is an end elevational view of the handle structure showing the further creasing of the blank along the diagonal gusset fold lines 36 and 37 which occurs as a consequence of the folding of the flange panels into angular position with respect to the handle panels 11 and 12.

The cuts 56 cause the wing portions 49 and 51 to crease relatively to the center tabs 42 and 43, preferably along the cuts rather than along a crease in line with the flange fold lines 27, 31. As a result the upper portions of the wings 49 and 51 tend to pull away from the flange panels 25, 29 for more convenient engagement with the web portion of the carrier which will now be described.

A representative form of a multicellular box is shown in Figure 4. This form of box embodies features disclosed and claimed in my co-pending application Serial No. 673,067, filed July 19, 1957, now Patent No. 2,901,157, in which details of its construction are described at length.

For the purpose of understanding of the present invention it is sufficient to note that the structure B of Figure 4 comprises two units 57 and 58 articulated to each other at 59. Each unit comprises a bottom panel 60, an outer wall panel 61, an inner wall panel 62, and a multi-cellular top structure 63, in each of which a number of cells are formed. There are end cells 64 and intermediate cells 65. The cells are separated from one another by transverse partitions 66 which also provide depending cell liners 67 with skirts 68, the bottom edges 69 of which are substantially equidistant from the bottom panel 60.

The bottom edge 69 of the cell liner or skirt of the central cells 65 may be cut back as shown at 68' for purposes which will become apparent hereinafter.

The illustrated cells are of substantially octagonal shape, two diagonal points of the octagon being the peaks 69' of the partitions 66, two further diagonal points are the base 70 of the V which the cells present in side view. The handle is preferably so shaped as to follow the contour of the cells.

Turning now to Figures 5 and 6, the formed handle A' is inserted into the two central cells 65 of the multicellular structure. In this position the auxiliary central folding creases 52 and 53 are in line with the points 70 in the inner wall panel 62. The outer edges of the flange panels 25 and 29 lie slightly inside the peaks 69' and form bottle separators. The box-engaging flaps 38 and 39 and more particularly the wings 49, 51 are hooked under the cell wall structure 67 of the central cells 65, and the edge 68' of the cutaway portion is in a position to be engaged along the fold lines 40 and 41 of the handle. The multicellular structure B is engaged and supported along a substantial length of the central cell liner in a position in which the weight contents in

70 the cells is supported in a favorable manner due to the fact that the engaged cell liners 67 are vertical and are prevented from buckling by being sandwiched between the handle panel and the flanges and the engaging flaps 49 and 51 which are folded back upon, and drawn tightly against, it.

As is seen from Figure 6 the handle may be fully depressed as shown in broken lines. In this position the carrier may be loaded, for example, with bottles 71 by conventional equipment and the handle provides full glass-to-glass contact protection for the bottles.

When pulled up, the wings 49, 51 hook under the cell walls or skirts 67 to support the carrier. It will be noted that the cut-back edge 68' forms an angle with the fold lines 40, 41 when the carrier rests on a flat surface. When the carrier is picked up by the handle, two halves of the carrier tilt relatively to each other about the fold line 59 until the inner side walls of the carrier lie face to face. This action causes the tops of the bottles to move outwardly thereby providing additional space for the hand of the person grasping the handle.

The clockwise tilting of the right portion of the carrier and the counterclockwise tilting of the left portion result in a change in the angle of the edges 68' which now assume the same angle as the fold lines 40, 41 of the handle, thus providing full-length engagement of the carrier cell wall edge 68' by the handle.

In assembled position the slits 26', 27', 30' and 31' of the handle lie in line with corners of the cell structure of the carrier as is particularly well visible in Figure 5. The removal of stock by the formation of the slits, particularly the removal of the score bead which forms on the back side of the board, permits the handle panels to rest snugly against the cell walls 67, thereby eliminating crowding and pinching of the walls 67 in the space between the main portion of the handle, e.g., panels 12, 28, 29 and the engaging flap 39 folded thereover.

The handle may readily be depressed again and pulled up, and will automatically reengage the edge 68 of the cell skirts.

Figure 7 shows another form which handles embodying the invention may assume.

The two handle panels 111 and 112 of the blank C are articulated along a central fold line 113 which may be supplemented by a number of further fold lines 113' spaced from, but parallel to, the central fold line 113. The handle panels have box-engaging flaps 138 and 139 articulated thereto along flap fold lines 140 and 141. The flaps comprise central securing areas 142 and 143 flanked by lateral wing portions 148, 149, 150 and 151. The central securing areas are separated from the wing areas by cuts 144, 145, 146 and 147.

Central folding creases 152 and 153 extend down the center of the handle panels to, and beyond, the flap fold lines 140 and 141 into the body of the flaps 138 and 139. Portions of the central creases may be intermittently cut scored as shown at 154 and 155. Slanted score lines 172, 173, 174 and 175 extend from the central creases 152 and 153 towards the lateral edges of the blank in the vicinity of the fold lines 113 and 113'.

V-cuts 176 and 177 may be provided in the securing areas 142 and 143 to facilitate the engagement of the handle with the carrier, as will later be described.

Prior to assembly of the handle with the multicellular box structure the engaging flaps 138 and 139 are folded back upon the handle panels 111 and 112, at which time the central areas 142 and 143 may be adhesively secured to the handle panels 111 and 112. The folding and gluing operation results in a structure C' shown in Figure 8.

For assembly of the handle with a multicellular box, the blank is folded along the fold line 113 and is creased along the central folding creases 152 and 153. This creasing operation again draws the engaging flaps 138 and 139 tightly against the handle panels 111 and 112. The handle is then inserted into the cells 64 of the box structure 57, as shown in Figure 9. The box 57 may be loaded while the handle is in the position in which its bottom edges 140 and 141 rest against the bottom

panel 60. When pulled up, the handle engages the transverse partition 66 with the engaging flaps 138 and 139 in the same manner as previously described in connection with Figures 5 and 6.

- 5 It will be noted that the handle C'' shown in Figure 9 engages the central partition 66 in such a way that the vertical crease line extending downwardly from the peak 69 (not visible in Figure 9, but identified by number 78 in Figure 4) lines up with the central creases 152 and 153. The board tends to form a bead at the back side by reason of the fact that the crease line 78 is originally formed by a creasing rule depressing the board between two spaced pieces of "make ready" in the cutting and creasing die. This bead tends to strike 10 the top edge of the box-engaging flaps 138 and 139 which for this reason are cut out in the form of the V as shown at 176 and 177 in Figure 7. The V-cuts permit the points 179 and 180 to engage the skirt of the webs before the bead of the crease 78 strikes the apex 20 of the V. Once engaged, the handle can be pulled up easily until the bottom edge 168 of the central partition 66 bears against the flap fold lines 140 and 141. In Figure 9 the handle C'' is shown in fully engaged position.
- 25 Figure 10 illustrates a variation in the use of the handle C'' in which the handle spans the central cell 65 and is inserted into the end cell 64. This arrangement is suitable for multicellular boxes having an odd number of cells arranged in line, whereas Figure 9 illustrates 30 an arrangement suited for an even number of cells.

What is claimed is:

1. A self engaging strap type handle of foldable sheet material, particularly for use with multicellular folding box structures, the handle comprising, a pair of substantially vertical handle panels folded in substantially the shape of an inverted U, the upper portion constituting a grip portion; a box engaging flap articulated to the end of each of the handle panels along a substantially horizontal flap fold line, said flap being folded back upon the panel to which it is articulated, at least the lower portions of the handle panels together with the folded-back flaps being bowed to form oppositely facing vertical channels, whereby the curved flap fold lines of both panels form a biconcave figure in plan view, the flaps are drawn tight against the handle panels, and are prevented from unfolding.
- 35 2. A self engaging strap type handle of foldable sheet material, particularly for use with multicellular folding box structures, the handle comprising, a pair of substantially vertical handle panels folded in substantially the shape of an inverted U, the upper portion constituting a grip portion; a box engaging flap articulated to the end of each of the handle panels along a substantially horizontal flap fold line, said flap being folded back upon the panel to which it is articulated, at least the lower portions of the handle panels together with the folded-back flaps being creased along at least one substantially vertical crease extending to said flap fold line to form 40 oppositely facing vertical channels in which the distance between the lateral edges of opposite handle panels is greater than the distance between the vertical creases of the opposite handle panels, said box engaging flaps having upwardly facing edges, said upwardly facing edges being spaced a substantial distance from the flap fold lines, the last named distance being measured along the said crease.
- 55 3. A self engaging strap type handle of foldable sheet material, particularly for use with multicellular folding box structures, the handle comprising, a pair of substantially vertical handle panels folded in substantially the shape of an inverted U, the upper portion constituting a grip portion; a flap articulated to the end of each of the handle panels along a substantially horizontal flap fold line, said flap comprising a central securing portion and lateral box engaging wing portions, said flap being 60 70 75

folded along said flap fold line back upon the panel to which it is articulated, the said central flap portion being adhered to said handle panel, at least the lower portions of the handle panels together with the folded-back flaps being bowed to form oppositely facing vertical channels, whereby the curved flap fold lines of both panels form a biconcave figure in plan view, the wing portions are drawn tight against the handle panels, and are prevented from unfolding.

4. A self engaging strap type handle of foldable sheet material, particularly for use with multicellular folding box structures, the handle comprising, a pair of substantially vertical handle panels folded in substantially the shape of an inverted U, the upper portion constituting a grip portion; a flap articulated to the end of each of the handle panels along a substantially horizontal flap fold line, said flap comprising a central securing portion and lateral box engaging wing portions, said wing portions being separated from said central portion by a cut terminating a substantial distance from the flap fold line, 10 said flap being folded along said flap fold line back upon the panel to which it is articulated, the said central flap portion being adhered to the handle panel, at least the lower portions of the handle panels with the folded-back flaps being bowed in such a way that the lateral 15 edges of the lower portion adjacent the wing portions of opposite handle panels are spaced farther apart than the central adhered portions of the opposite handle panels.

5. A self engaging strap type handle of foldable sheet material, particularly for use with multicellular folding box structures, the handle comprising, a pair of substantially vertical handle panels folded in substantially the shape of an inverted U, the upper portion constituting a grip portion; a flap articulated to the end of each of the handle panels along a substantially horizontal flap fold line, said flap comprising a central securing portion and lateral box engaging wing portions, said wing portions being separated from said central portion by a cut terminating a substantial distance from the flap fold line, 30 said flap being folded along said flap fold line back upon the panel to which it is articulated, the said central flap portion being adhered to the handle panel, at least the lower portions of the handle panels with the folded-back flaps being creased along at least one substantially vertical crease extending to said flap fold line, the direction of creasing being such that the wing portions of opposite handle panels are spaced farther apart than the 35 distance between said central adhered portions.

6. A self engaging strap handle of foldable sheet material, particularly for use with multicellular folding box structures having cells of substantially polygonal outline, the handle comprising, a pair of substantially vertical handle panels folded in substantially the shape of an inverted U, the upper portion constituting a grip portion; lateral flange panels articulated to the handle panels along substantially vertical flange fold lines; a box engaging flap articulated to, and extending across, the end of the handle panel and its bordering flange panels along a substantially horizontal flap fold line, said flap being folded along said flap fold line back upon the handle panel and its bordering flange panel to which it is articulated, the flange panels being folded relatively to the handle panels along said flange fold lines to assume an angular position with respect to the handle panels at least within the lower portion of the handle which comprises the flaps, the direction of folding being such that the handle panels are spaced apart less than the flange panels which flare away from it, the folding of the flange panels relatively to the handle panels resulting in creasing of the flaps, whereby the flaps are drawn tight against the handle panels and the flange panels are prevented from unfolding.

7. A self engaging strap handle of foldable sheet material, particularly for use with multicellular folding box

structures having cells of substantially polygonal outline, the handle consisting of a blank of foldable sheet material, folded back-facing-back along a top fold line, the blank comprising a pair of substantially vertical centrally disposed handle panels articulated to each other along said top fold line and a pair of lateral flange panels articulated to each of the handle panels along substantially vertical flange fold lines, said flange fold lines extending to said top fold line, the flanges of opposite handle panels being likewise articulated to each other along said top fold line, said flange panels being traversed by diagonal gusset fold lines extending from the intersection of said top fold line with said flange fold lines; a box engaging flap articulated to, and extending across, the end of the handle panel and its bordering flange panels along a substantially horizontal flap-fold line, said flap being folded along said flap fold line back upon the handle panel and its bordering flange panel to which it is articulated, said flange panels being folded relatively to the handle panel along said flange fold lines to assume an angular position with respect to the handle panels, the direction of folding being such that the handle panels are spaced apart less than the flange panels which flare away from it, the folding of the flange panels relatively to the handle panels resulting in creasing of the flaps substantially in line with the flange fold lines, whereby the flaps are drawn tight against the handle panels and the flange panels and are prevented from unfolding.

8. A self engaging strap handle of foldable sheet material, particularly for use with multicellular folding box structures having cells of substantially polygonal outline, the handle comprising, a pair of substantially vertical handle panels folded in substantially the shape of an inverted U, the upper portion constituting a grip portion; lateral flange panels articulated to the handle panels along substantially vertical flange fold lines; a box engaging flap articulated to, and extending across, the end of the handle panel and its bordering flange panels along a substantially horizontal flap fold line, said flap being folded along said flap fold line back upon the handle panel and its bordering flange panels to which it is articulated, the flap comprising a central securing portion adhered to said handle panel, and lateral box engaging wing portions, said wing portions being wider than said flange panels so as to extend beyond the flange fold lines towards said securing portion in folded-back position, the flange panels being folded relatively to the handle panels along said flange fold lines to assume an angular position with respect to the handle panels at least within the lower portion of the handle which comprises the flaps, the direction of folding being such that the handle panels are spaced apart less than the flange panels which flare away from it, the folding of the flange panels relatively to the handle panels resulting in creasing of the wing portions substantially in line with said flange fold lines, whereby the flaps are drawn tight against the handle panels and the flange panels and are prevented from unfolding.

9. A self engaging strap handle of foldable sheet material, particularly for use with multicellular folding box structures having cells of substantially polygonal outline, the handle consisting of a blank of foldable sheet material, folded back-facing-back along a top fold line, the blank comprising a pair of substantially vertical centrally disposed handle panels articulated to each other along said top fold line and a pair of lateral flange panels articulated to each of the handle panels along substantially vertical flange fold lines, said flange fold lines extending to said top fold line, the flanges of opposite handle panels being likewise articulated to each other along said top fold line, said flange panels being traversed by diagonal gusset fold lines extending from the intersection of said top fold line with said flange fold lines; a box engaging flap articulated to, and extending across, the end of the handle panel and its bordering flange panels along a substantially horizontal flap-fold line, said flap being folded along said

flap fold line back upon the handle panel and its bordering flange panels to which it is articulated, said flap comprising a central securing portion adhered to said handle panel, and lateral box engaging wing portions, said wing portions being separated from said central portion by a cut terminating a substantial distance from the flap fold line, said cut overlying the handle panel, said wing portions being wider than said flange panels so as to extend beyond the flange fold lines towards said securing portion, said flange panels being folded relatively to the handle panel along said flange fold lines to assume an angular position with regard to the handle panel, the direction of folding being such that the handle panels are spaced apart less than the flange panels which flare away from it, the fold-

ing of the flange panels relatively to the handle panels resulting in creasing of the wing portions substantially in line with the flange fold lines, whereby the flaps are drawn tight against the handle panels and the flange panels and are prevented from unfolding.
